LATCH

Johnnie L. Leatherman, Millsap, Tex.

Application July 5, 1951, Serial No. 235,130

4 Claims. (Cl. 292—99)

1

This invention relates to latching devices for doors, and it has particular reference to a latch for screen doors, and its principal object resides in the provision of a latch assembly which is especially adaptable to use for securing screen doors, and capable of being locked from the inside, as desired.

An object of the invention is that of providing a simple and economical structure comprising a mounting bracket having a tensioned latch lever thereon and having means for automatically actuating the lever when the door is closed.

Broadly, the invention contemplates the provision of a latch which is capable of use in securing doors, gates, and the like, and providing a latch pin mountable on a door or gate post and adjustable to a variety of spacings from the door latch by rotating the mounting plate.

While the foregoing objects are paramount, other and lesser objects will become manifest as the description proceeds, taken in connection with the appended drawings wherein:

Figure 1 illustrates the invention in side elevation in latched position, the mounting bracket being shown in longitudinal section on lines 1—1 of Figure 3.

Figure 2 is a front elevational view of the invention in latched position.

Figure 3 is a plan view of the invention in latched position, showing the locking device in operation, the door and door-post being illustrated fragmentarily in transverse section, and

Figure 4 is a side elevational view of the invention in unlatched position, the mounting bracket being shown in vertical section.

Accordingly, the invention comprises a mounting bracket which is formed with a plate 10 which has integral flanges 11 and 12 extending at right angles therefrom and which are substantially triangular in form, as apparent in Figures 1 and 4. A latch lever 13 is supported for operation on a pivot 14 which is journaled at each end in the flanges 11 and 12.

The lever 13 has a cam 15 formed therewith which extends at right angles from the longitudinal plane of the lever and on the opposite side of the pivot 14 therefrom. A flat arched spring 16 is supported on the plate 10 between the flanges 11 and 12 and the cam 15 has a bearing thereagainst whereby the lever 13 is arrested in latched or unlatched positions, as illustrated in Figures 1 and 4, respectively. A chain 17 has one end secured to the outer end of the lever 13 in a slot 18 formed therein, and shown in Figures 2 and 3. The chain 17 is arranged through a bore 19 in

the stile 20 of the door so that the lever 13 can be operated from the outside of the door.

Integral with the lower end of the lever 13 and opposite the pivot 14 is formed a hook 21 which is adapted to engage a latch pin 22 extending from a plate 23 which is secured by screws 24, or other device, to a post 25 of the door frame. The pin 22 is eccentrically located on the plate 23, as shown in Figure 1, so that when the latter is rotated, or arranged at different angular positions, the pin 22 can be spaced from the door stile 20 as required to properly secure the door.

Rearwardly of the hook 21 is an integral lug 26 which is arranged at right angles to the axis 15 of the pivot 14, and it has the function of engaging the pin 22, as illustrated in Figure 4, to cause the hook 21 to overreach the pin 22 to latch the door in the position shown in Figure 1, the cam 15 meanwhile having a sliding contact with the spring 16 to retain the hook 21 on the pin 22. Obviously, when the lever 13 is moved on its pivot 14 to the position shown in Figure 4, either from the inside or by the chain 17 from the outside, the door can be opened. As it moves shut the hook 21 automatically engages the pin 22.

The lever 13 can be locked in its operative position, as shown in Figure 1, by a locking lever 27 which is also pivotally supported between the flanges 11 and 12 on a pin 28 located above and rearwardly of the pivot 14. A cam 29 is formed on the lever 27 opposite its operative end and engages the spring 16 which secures the lever 27 in locked and unlocked positions, as in Figures 1 and 4, the unlocked position also being shown in dotted lines in Figure 1.

A tab 30 is formed on one side of the member 27 for operating the same. The tab 30 can be formed on either or both sides of the member 27 so that the latch assembly can be placed on either right or left hand doors. The lever 27 may also be formed so that it can be reversible, or capable of being installed so that the tab 30 may extend from either side of the assembly. The cam 29 will retain the lever 27 in either of its positions by reason of its association with the spring 16.

Manifestly, the structure herein shown and described is capable of certain changes and modifications from time to time, by persons skilled in the art, without departing from the spirit and intent of the invention or the scope of the appended claims.

What is claimed is:

1. In a latch for screen doors cooperating with a latch pin on the door frame, a mounting bracket

et having a pair of flanges integral with its sides and means for securing the same to a screen door, a latch lever formed with a hook on its lower end and engageable with said latch pin, a cam formed with said lever at its pivot, a lug 5 arranged through said door for operating said lever, and a locking member for securing said lever in locked position.

2. In a latch for screen doors, in combination, a latch plate attachable to a door having a pair 15 of right-angular flanges formed therewith, a latch lever pivotally arranged between said flanges and formed with a hook engageable with a latch pin, a cam formed on said lever opposite said hook, a spring arranged on said plate between said flanges and engageable by said cam to actuate said lever to locked and unlocked positions, means extending through said door for operating the said lever, and a locking member 25 having a cam thereon pivoted between said flanges whereby to lock said lever in engagement with said latch pin.

3. In a latch for doors cooperating with a latch pin on a door frame, in combination, a latching lever and a mounting bracket providing a pivotal support therefor, a hook formed on the lower end of said lever engageable with a latching pin,

5 a lug formed with said lever opposite said hook and engageable with said latch pin to guide said hook thereupon, a cam formed with said lever and a spring on said mounting bracket engageable with said cam to retain the same in latched and unlatched positions, means arranged through said door for actuating said latch lever, and a locking member for said lever having a pivotal mounting on said bracket in operative association with said lever.

4. In a locking device for doors, in combination, a latch lever having a pivotal mounting between a pair of flanges of a mounting bracket on said door, a hook formed with the lower end of said lever and forwardly of the pivot of said lever, a lug integral with said lever rearwardly of said hook and engageable with a latch pin to guide said hook thereupon, a cam formed with said lever and extending rearwardly thereof, a spring in said mounting bracket engageable by said cam, a flexible means for operating said lever from the exterior of said door, and a locking device for said latch lever.

JOHNNIE L. LEATHERMAN.
